(57) **CLAIM**

The ornamental design for a wearable semiochemical retainer, as shown.

DESCRIPTION

FIG. 1 is an upper front right-side perspective view of a wearable semiochemical retainer in accordance with the present design;

FIG. 2 is a lower rear left-side perspective view of the wearable semiochemical retainer shown in FIG. 1;

FIG. 3 is a top view of the wearable semiochemical retainer shown in FIG. 1;

FIG. 4 is a bottom view of the wearable semiochemical retainer shown in FIG. 1;

FIG. 5 is a front view of the wearable semiochemical retainer shown in FIG. 1, which is mirror symmetrical with the rear view;

FIG. 6 is a left-side view of the wearable semiochemical retainer shown in FIG. 1;

FIG. 7 is a right-side view of the wearable semiochemical retainer shown in FIG. 1; and,

FIG. 8 is a perspective view showing the wearable semiochemical retainer shown in FIG. 1 in an open position.
